UNITED STATES PATENT OFFICE.

DAVID HINDAHL, OF CHICAGO, ILLINOIS, ASSIGNOR TO NATIONAL DUMP CAR COMPANY, OF CHICAGO, ILLINOIS, A CORPORATION OF MAINE.

DUMP-CAR-DOOR LATCHING MECHANISM.

Application filed July 3, 1922. Serial No. 572,427.

To all whom it may concern:

Be it known that I, DAVID HINDAHL, a citizen of the United States, residing at Chicago, in the county of Cook and State of Illinois, have invented certain new and useful Improvements in Dump-Car-Door Latching Mechanism, of which the following is a specification.

This invention relates to latches for locking the doors of dump cars, and particularly to latches comprising a pair of oppositely acting pivoted members, and means through which these members can be swung into and out of latching relation to the door by an operator standing at a vantage point outside the path of the lading on discharge.

The object of the invention is to provide a simple, efficient and durable construction for the purposes stated; and, accordingly, the invention consists in uniting two pivoted latches by a thrust bar or link which forces them to act simultaneously in moving to and from latching position, and providing on one of the latches, a leverage extension preferably comprising a socket integral with the latch, and a lever arm releasably fitted in said socket, through means of which both latches may be operated; the thrust bar or link being preferably connected with the lever-actuated latch on the opposite side of the pivot from its connection with the other latch so that the latches are moved oppositely; and a locking dog movable into and out of dogging relation to one of the latches being, through the medium of the thrust bar or link, rendered controlling as to the other latch, as well.

In the accompanying drawing, in which the preferred embodiment of the invention is shown by way of illustration—

Figure 1 is a side elevation of the latching mechanism together with the portions of a dump car with which it is immediately concerned;

Figure 2 is a similar view showing the latching mechanism on an enlarged scale, in unlatching position; and

Figure 3 is a top plan view of parts shown in Figure 2.

1 represents the side of a dump car, and 2 the projecting portions of a drop door thereon, which projecting portions are to be engaged by latches for the purpose of releasably holding them in elevated position. 3 and 4 represent a pair of latches pivoted, re-

spectively, at 5 and 6 so that they are adapted to move into and out of latching relation with the projections 2.

7 represents a pivotal locking dog mounted in position to permit its camming surface 8 to wedge against the back of one of the latches, preferably latch 3, and having a stud 9 by which it may be displaced to and from its dogging position and its neutral position of rest upon the stop 10.

In order to cause the latches 3 and 4 to move simultaneously, to and from latching position, and to bring both latches under control of the single locking dog 7, a thrust bar or coupling link 11 is pivoted to the latch 3 at 12 between its pivot 5 and latching end 3^a, and to the latch 4 at the point 13 which is on the opposite side of the pivot 5 from the latching end 4^a. Consequently, movement of either latch to or from latching position will enforce a like movement in the other latch, and dogging one latch against movement will, indirectly, dog the other latch.

In order that the movement of the latches 3 and 4 may be controlled with force from a vantage point away from the path of discharging cargo, latch 4 is provided with an operating arm 14 extending therefrom with sufficient offset from its pivot 6 to render the control easy and this arm is preferably united with the latch through the medium of a socket member 15 which renders the arm removable from the latch. Socket member 15, or the arm, if the latter were integral with the latch, in the construction shown, affords a properly offset extension to receive the pivot 13 of the connecting link 11. Preferably, the socket 15 will be in a plane offset outward from the plane of the bearing for pivot 13.

It will be seen that coupling link 11 as well as the socket 15 is related to the latches 3 and 4 in a manner to add weight to that of the latches in the direction of latching movement, thereby increasing the safety of the device in the event of the locking dog 7 being neglected.

I claim:

1. In combination with a dump car door, latching mechanism comprising a pair of pivoted latches, and a coupling link connected with said latches and adapted to insure like movements in them; said latches being presented in opposite directions; and

said link being connected to them on opposite sides of their pivots.

2. In combination with a dump car door, a pair of pivoted latches for releasably engaging said door, a coupling link uniting said latches and adapted to enforce identical movements in them, and a controlling arm mounted upon and rigidly extending from one of said latches and forming therewith a lever the fulcrum of which is the pivot of the latch.

3. In combination with a dump car door, a pair of latches for releasably engaging said door, a coupling link uniting said latches and adapted to enforce identical movements in them, and a controlling socket extending from one of said latches in a direction to urge the latch toward latching position by the gravitation of the socket.

20 4. In combination with a dump car door,

a pair of latches for releasably engaging said door, a coupling link uniting said latches and adapted to enforce identical movements in them, and a controlling arm extending from one of said latches; said latches being presented in opposite directions, said arm providing an extension from its latch on the opposite side of the pivot from the latching end, and said coupling link being connected to the arm carrying link through the medium of said extension. 25

5. In combination with a dump car door, latching mechanism comprising a pair of oppositely swinging latches, and a coupling link connected with said latches and adapted to insure opposite movements in them. 30

Signed at Chicago, Illinois, this 16th day of June, 1922.

DAVID HINDAHL.
